(57) **CLAIM**

The ornamental design for a solar trailer, shown and described.

DESCRIPTION

FIG. 1 is a left, top, rear perspective view of the solar trailer in a use configuration thereof;

FIG. 2 is a right, top, front perspective view of the solar trailer in the use configuration thereof;

FIG. 3 is a top view of the solar trailer in the use configuration thereof;

FIG. 4 is a right view of the solar trailer in the use configuration thereof;

FIG. 5 is a left view of the solar trailer in the use configuration thereof;

FIG. 6 is a rear view of the solar trailer in the use configuration thereof;

FIG. 7 is a front view of the solar trailer in the use configuration thereof;

FIG. 8 is a left, top, rear perspective view of the solar trailer in a transport configuration thereof;

FIG. 9 is a right, top, front perspective view of the solar trailer in the transport configuration thereof;

FIG. 10 is a top view of the solar trailer in the transport configuration thereof;

FIG. 11 is a right view of the solar trailer in the transport configuration thereof;

FIG. 12 is a left view of the solar trailer in the transport configuration thereof;

FIG. 13 is a rear view of the solar trailer in the transport configuration thereof; and,

FIG. 14 is a front view of the solar trailer in the transport configuration thereof.

The broken lines shown in the drawing are for illustrative purposes only and form no part of the claimed design.
